UNITED STATES PATENT OFFICE

2,401,504

AIRBRUSH DEVICE

Jens A. Paasche, Chicago, Ill.

Application December 4, 1943, Serial No. 512,846

3 Claims. (Cl. 299—88)

1

The present invention relates to spray or air brush devices and more particularly to an improved air brush device adapted for applying hot or cold protective coatings.

The present invention is particularly concerned with improvements in spraying or air brush devices for the application of protective coatings such as heavy oils, paraffins, greases, asphalt compounds, glues, resins, waxes, et cetera, which must be heated so as to be in a fluid state of a desired viscosity so that the material sprayed may be properly atomized. In spraying such materials it furthermore is desirable to maintain the sprayed material at a temperature or viscosity so that the material will adhere and cohere properly on the object to be coated. Accordingly, the present invention contemplates a device which heats the material to be sprayed and means are provided for supplying a heated aeriform substance to atomize the material being sprayed and to envelope such sprayed material with an atmosphere which does not cool or materially reduce the desired viscosity of the material. In the application of certain materials it furthermore may be found desirable to use in place of air, such as is the common aeriform substance used, some other gas which would prevent oxidation of the sprayed material.

It therefore is an object of the present invention to provide an improved spraying device as set forth above, wherein electrical heating means are provided which are thermostatically controlled to obtain the desired temperatures of the aeriform substance and the material to be sprayed.

A still further object of the present invention is to provide an air brush device of the type set forth above which is readily supported in one hand and which is provided with suitable control devices whereby the desired rate of flow and pattern of spray may be controlled.

Other and further objects will subsequently become apparent by reference to the following description taken in connection with the accompanying drawings, wherein:

Fig. 1 shows a perspective side view of the apparatus comprising the present invention;

Fig. 2 is a partial cross-sectional view of the apparatus shown in Fig. 1;

Fig. 3 is a view along the line 3—3 of Fig. 2; and

Fig. 4 is a view in the opposite direction from Fig. 3 along the line 4—4 of Fig. 2.

Referring more particularly to Fig. 1 of the drawings, it will be seen that there has been pro-

2

vided a spraying apparatus having a material container or chamber, such as 11, which may be cylindrical in form as shown and provided with a cover 12 which may be securely fastened in position on the chamber 11 by suitable fastening means 13. Such suitable fastening means 13 may comprise a member having two clamping ears, such as 14, connected to an intermediate supporting structure 15 which is provided with a threaded aperture wherein a screw member 16 may be arranged to operate by a handle member 17. The entire assembly is conveniently held in one hand by holding a handle 49 which is connected to a spraying mechanism 19 interposed between a handle 49 and the material chamber 11. A spraying apparatus 19 is controlled by a trigger 21 which operates certain valve mechanisms controlling the flow of an aeriform substance and material to a nozzle assembly 22 mounted at the front of the spraying mechanism 19. The nozzle 22 through suitable valve mechanism is arranged for communication with the material passage 23 interconnecting a material chamber 11 and a spraying apparatus 19; and also with an aeriform substance under pressure which is supplied through a suitable hose or conduit 24. The hose or conduit 24 is connected through suitable coupling means 25 to a point adjacent a lower portion of the material chamber 11.

Immediately below the material chamber 11 there is another chamber 26 of slightly greater diameter wherein there is provided a circuitous aeriform passage 20. Suitable heating means are provided for heating both the aeriform passage 20 and the material chamber 11 so that heated material and a heated aeriform substance may be supplied simultaneously to the spraying apparatus 19. The temperature of the chamber 11 is controlled by a suitable thermostat 27 mounted beneath the lower chamber 26. Electric power is supplied through a suitable connecting cord 28 and a plug assembly associated with the apparatus in the vicinity of the thermostat 27.

The details of such an arrangement will become more apparent by reference to Figs. 2, 3 and 4, wherefrom it will be seen that the aeriform passage 20 may be positioned in the form of a spiral immediately adjacent the bottom of the material chamber 11. One end of the aeriform passage 20 is joined with a threaded coupling member 29 supported in a portion of the wall of the lower chamber 26 and provided with suitable threaded portions for cooperation with the threaded ring coupling member 25. The other

end of the aeriform passage 20 extends downwardly to the rear of the spraying apparatus 19. Immediately beneath the coiled or spiral portion of the aeriform passage 20 there is mounted a heating element 31 provided with a pair of electric terminals 32 and 33 which are joined by suitable conductors 34 and 35 to the thermostat assembly 21. The thermostat assembly 21 may comprise any suitable thermostat arrangement well known in the prior art. The lower chamber 26 is supported from the bottom of the upper material chamber 11 by a stud 36 mounted adjacent the central portion of the bottom of the upper chamber 11. The other extremity of the stud 36 is threaded so as to receive a nut 37 which bears against an insulating plate 38 positioned adjacent the bottom of the lower chamber 26. On the inside of the lower chamber 26 there are provided a plurality of spacing members 39 and 41 above which is mounted the heating element 31 which is positioned between two suitable supporting plates 42 and 43. The upper supporting plate 43 is retained in position by a corrugated plate 45 provided adjacent its center with a collar portion 46 which is threaded at the interior so as to engage the threaded portion of the stud 36. The threaded collar portion 46 together with the nut 37 therefore operate to retain in position the various elements between the fiber plate 38 and the upper corrugated supporting plate 45.

The spraying apparatus 19 comprises a forward portion or nozzle assembly generally indicated by the numeral 47, a central body portion 48 which carries the nozzle assembly 47 and a handle 49 by which the body portion 48 may be supported. Material from the chamber 11 is introduced in the nozzle assembly 47 through a passage 51 formed of an angularly upstanding portion 52 in the frame 48 and interconnected by a suitable coupling member 53 which threadedly engages the member 52 and a threaded opening adjacent the bottom of the material chamber 11. The angularly disposed material passage 52 joins with a horizontal passage 54 having supported therein a centrally disposed needle member 55 which cooperates with an orifice 56. The needle 55 passes through a bearing portion 57 in the body 48 and through a packing chamber 59 containing suitable packing rings and a spring for holding the packing rings in compressed position. Just beyond the packing member 59 the needle 55 is secured to a longitudinally movable member 61. The rear extremity of the needle 55 is supported in a suitable bearing surface 62 formed in the frame 48. Interposed between the bearing 62 and the longitudinally movable member 61 is a spring 63 which urges the needle 55 forwardly against the orifice 56. The longitudinally movable member 61 extends horizontally and downwardly through a suitable opening 64 in the frame 48 and upwardly to be secured to a longitudinally movable rod 65 mounted in a suitable bearing in the frame 48. The rod 65 is provided at its rear end with a reduced portion arranged to engage a recess in a valve member 66 which cooperates with a valve opening 67 in the frame 48. At an intermediate point adjacent that portion of the longitudinally movable member 61 which extends through the opening 64 there is provided an elongated slot arranged to cooperate with a pin 68 mounted in a handle lever 69. The handle lever 69 is pivotally mounted adjacent its upper end by a suitable pin 71. The lower extremity of the handle lever 69 may be enclosed by a suit-

able gripping member or casing 21. An angular displacement of the lever 69 toward the rear causes the pin 68 to engage the slot in the member 61, thereby to produce a rearward longitudinal motion which moves the needle 55 away from the orifice 56 and at the same time moves the valve 66 away from the valve seat 67. The valve 66 is biased toward closure by a suitable spring 73 mounted between the valve 66 and an end cap 74 which is secured to the frame 48 by a coupling member 75. The end cap 74 is secured to the lower extremity of the aeriform passage 20.

The aeriform passage 20 which is united with the end cap 74 therefore communicates with a passage 76 in which the spring 73 and the valve 66 are positioned. When the valve 66 is moved rearwardly from the seat 67, communication is had between the passage 76 and another passage 77 which extends forwardly to an annular passage 78 which is in communication with a plurality of longitudinal passages 79. Some of the passages 79 are also arranged for communication with another passage 81 in which there is mounted a valve member 82 which cooperates with a valve seat interconnecting a pair of passages 83 and 84. The passages 83 and 84 are in communication with a plurality of apertures or orifices 85 and 86 in the nozzle assembly 47. These passages 85 and 86 in the nozzle assembly are for the purpose of providing a fanning effect in accordance with a more detailed description set forth in my Patent No. 2,139,133, dated December 6, 1938.

The aeriform passage 79 also communicates with aeriform passage 87 which extends to an orifice 88 which surrounds the material orifice 56. The nozzle assembly 47 is arranged to be demountable for ready cleaning by a suitable clamping ring 89 provided about its periphery with suitable protuberances or knurlings. In order to provide access to the packing chamber 59 for renewing the packings, a forward portion of the gun may be separated by uncoupling the coupling 53 and by loosening a clamping ring 81. The packing rings then may be removed and renewed.

In order to control the proportion of air or an aeriform substance supplied to the passages 83 and 84 and the cooperating ports 85 and 86, the valve 82 is arranged to be adjustable. The valve head 82 is mounted on a threaded stem 92 terminating in a knob 93. The knob 93 is locked to the stem 92 by a cooperating lock nut member 94 so that the knob 93 and the lock nut member 94 are moved as a unitary assembly. The valve head 82 together with the stem 92, the knob 93 and the lock nut portion 94 are mounted within a nipple or housing 95 formed integral with the central body portion 48 of the spraying apparatus. The nipple or housing 95 engages at its outer extremity a plug-like threaded member 96, the interior of which is also threaded to engage the threads on the valve stem 92. Suitable packing and a spring are interposed between the head 82 of the valve assembly and the threaded member plug 96. Thus by rotation of the knob 93 the position of the valve head 82 may be set so that a predetermined amount of the air supplied through the spraying apparatus will be projected from the ports 85 and 86 to give the desired fanning effect.

The main frame or body 48 of the spraying apparatus is provided adjacent its rear portion with a downwardly angularly projecting member

97 which is threaded on its interior so as to be engaged by a bolt or threaded tubular member 98 having at the other extremity a head or nut 100 which secures in position the handle 49. Interposed between the handle 49 and the main frame 48 of the spraying apparatus is a heat insulating member 99 arranged so that when the heated aeriform substance passes through the spraying apparatus for any appreciable amount of time, the heated body of the spraying apparatus will not come in contact with the operator's hand. For the same reason the handle-like portion 21 on the trigger lever 69 may also be formed of a suitable heat insulating material. In order to regulate the degree of movement of the lever 69, the handle 49 is provided adjacent its upper portion with an adjusting screw 101 having a threaded portion arranged to engage a suitable threaded opening 102 formed in the handle. The adjusting screw 101 is provided with a coiled spring 103 arranged to retain the screw in adjusted position. Extending forwardly of the knurled nut-like portion 101 of the adjusting screw is a stud 104 which engages the rear of the handle 21, thereby to limit the degree to which the valve head 66 and the needle valve 55 are moved from their respective cooperating seats. The flat insulating plate 38 interposed between the lower chamber 26 and the main body 48 of the spraying apparatus further assists in insulating the spraying apparatus from the heat generated by the heating element 31.

From the above description of the apparatus it therefore becomes apparent that there has been provided a unitary assembly which is readily supported in one hand of the operator by the handle 49 and the operation thereof controlled by actuation of the lever 69. It thus will be appreciated that the cord 28 is connected to a suitable electrical outlet to supply electrical energy to the heating element 31 which energy is controlled in accordance with the setting of an adjustable thermostat assembly 27. A suitable gaseous fluid, such as air, is connected to the hose 24 to supply an aeriform substance to the passage 20 wherein the substance will be heated to the desired temperature. The material such as asphalt, grease, or other protective coating contained within the material chamber 11, is heated so as to be in a fluid state with the desired degree of viscosity. After the apparatus has been heated for a sufficient length of time, the handle 21 is actuated slightly to permit a passage of the aeriform substance through the spraying apparatus to bring it to proper operating temperature. Thereafter the handle 21 may be actuated to its fullest extent so as to clearly open the material passage by the withdrawal of the needle 55 from the port or orifice 56. The material which leaves the nozzle assembly from the orifice 56 is surrounded by

heated aeriform substance projected through the orifice 88 so as to surround the material and to atomize it. The particular pattern desired in the form of atomized material is controlled by the ports 85 and 86. The material to be applied to an object to be coated, therefore, is projected in atomized form in an atmosphere which envelopes it and maintains it at a predetermined temperature so as to obtain good adherence and coherence of the material particles to the object to be coated and to each other. The heated aeriform substance prevents the material from becoming cooled prior to the application to the object to be coated and where desired the aeriform substance may be of such a nature as to prevent oxidation of the material being applied.

After the apparatus has been placed in operation it frequently is necessary to interrupt the spraying operation to handle the work or perform other duties. In order that the apparatus will not cool off so as to bring about a congestion of the heated material passage, the valve 66 is provided with a fine slot 70 or hole so that a small amount of heated air is permitted to escape, thereby to keep the head and body portions of the gun heated.

While the particular embodiment of the invention has been disclosed, in order to readily explain the invention it, of course, will be understood that I do not wish to be limited thereto since obviously modifications and alterations may be made in the instrumentalities employed and in their arrangements without departing from the spirit and scope of the invention as set forth in the appended claims.

The invention is hereby claimed as follows:

1. In a sprayer for viscous material, a nozzle, a container for the material to be sprayed, means providing communication between said nozzle and said container, an electric heating element positioned adjacent an exterior surface of said container, a heat exchanger coil, means positioning said coil in juxtaposition with said exterior surface of said container between said surface and said heating element, means for supplying a gaseous fluid under pressure to said heat exchanger coil, a passage providing communication between said heat exchanger coil and said nozzle, said heat exchanger coil being formed with an unobstructed area of such extent that proper heating of both the viscous and the gaseous fluid is simultaneously effected.
2. A sprayer as in claim 1 in which said surface is the bottom of the container.
3. A sprayer as in claim 1 in which said surface is the bottom of the container and in which said nozzle is that of a paint gun and said container is positioned above the paint gun.
